UNITED STATES PATENT OFFICE.

DAVID LESLIE MOBLEY, OF LOS ANGELES, CALIFORNIA.

AEROPLANE.

1,007,789.

Specification of Letters Patent.

Patented Nov. 7, 1911.

Application filed January 5, 1911, Serial No. 600,943. Renewed September 13, 1911. Serial No. 649,196.

To all whom it may concern:

Be it known that I, DAVID LESLIE MOBLEY, a citizen of the United States, residing at Los Angeles, in the county of Los Angeles 5 and State of California, have invented a new and useful Aeroplane, of which the following is a specification.

This invention relates to the class of flying machines known as aeroplanes, in which 10 the machine is sustained in the air by the reaction on the air of an aeroplane surface forced through the air by propelling means.

The main object of the present invention is to provide a machine of this character in 15 which the aeroplane surfaces are so distributed with reference to one another and to the center of gravity of the machine that lateral and longitudinal stability will be provided for without the use of movable 20 stabilizing devices.

Another object of the invention is to provide an aeroplane having upper and lower planes in which the said planes are so formed and disposed that substantially the 25 full effect of both planes is obtained both in forward propulsion and in descending.

Other objects of the invention will appear hereinafter.

The accompanying drawings illustrate the 30 invention, and referring thereto: Figure 1 is a perspective of the frame and aeroplane portions of the machine. Fig. 2 is a plan of the machine. Fig. 3 is an inverted plan of the machine. Fig. 4 is a front elevation, 35 and Fig. 5 is a horizontal section of the machine. Fig. 6 is a detail view of the operating gearing for the vertical rudder.

The machine comprises two main upper 40 aeroplane members 1 mounted at each side of the longitudinal axis of the machine, and two lower aeroplane members 2 below the members 1, all of said aeroplane members being mounted on a rigid frame consisting of upper and lower frame portions connected and spaced apart by vertical struts 3. Each of the said aeroplane members 1 and 2 is of triangular form. The lower aeroplane members are of smaller dimensions than the upper aeroplane members 1, so as to more 45 fully expose the upper aeroplane members to the reaction of the air. The upper frame portion comprises front bar 4, rear bar 5, bars 6 extending obliquely from the front bar to the rear bar along the edges of the 50 aeroplane members 1 and constituting, with the intervening portions of the front bar,

the stretching frames for said aeroplane members. A brace bar 7 extends from the front bar 4 longitudinally of each aeroplane member 1 and is connected at its rear end to the rear bar 5. The lower frame portion similarly comprises front and rear bars 4' and 5' and oblique bars 6'. The lower aeroplane members 2, being smaller than the upper aeroplane members 1 are preferably 60 supported by stretching frame bars 8 and 9, forming a triangle, attached to the lower frame bars 6' by extensions 8' of the front bar 8, and by an extension 9' of a brace bar 7' extending longitudinally of the lower 65 aeroplane member. The machine also preferably comprises a rear aeroplane member 10 mounted in fixed position on the upper frame and preferably in the same plane as the aeroplane members 1, with its forward 70 end connected to the member 1 intermediate its ends and extending rearwardly beyond the rear ends of the members 1, said rear aeroplane member 10 being also in the form of a triangle with its base presented 75 at the front edge thereof, a front bar 11 being provided at this edge, connected to oblique bars 6 and oblique bars 12 extending from the ends of bar 11 to the apex of the triangle at the rear end thereof. Below 80 this rear aeroplane member is mounted an elevator member or horizontal rudder 14 carried by a shaft 15 pivotally mounted in bearings 16 on a bottom frame bar 17 connected to the bottom frame bars 6', this horizontal rudder being provided with means 85 for adjustment or control, as hereinafter set forth. A vertical rudder 18 is also provided, carried by a shaft 19 mounted in bearings 90 20 on the rear ends of upper and lower frame bars 12 and 17.

A longitudinal frame 22 extends below the lower frame portion and is hung therefrom by bars 22' at its ends, said frame 22 carrying the aviator's seat 23, and also carrying the running gear, said running gear comprising, for example, a front wheel 24 connected by post 25 to the front of the frame 22 and two rear wheels 26 connected to the rear bar 27 of the frame by posts 28. Engines or motors 30 are mounted in suitable position on the machine, for example, on the lower frame bars 6' and 7' at the rear portion of the machine, the shafts 31 of said engines carrying the propellers or fans 32 105 and the axis of said shafts being preferably 110 in the plane of the longitudinal axis or

median lines of the triangular aeroplane surfaces 1, but between the upper and lower aeroplane surfaces.

The means for controlling the horizontal 5 rudder may consist of rods 34 sliding longitudinally in the sub-frame 22 and connected by bars 35 to said horizontal rudder, said rods being operated by a lever 36 near the aviator's seat. Another controlling 10 means, such as the hand wheel 37 near the aviator's seat, is connected by shaft 38 and gears 39 and 40 to the shaft 19 of the vertical rudder.

While any suitable construction of aeroplane surfaces may be used in connection 15 with the above described construction, I prefer to employ the form shown in the drawings consisting of a flexible fabric, such as cloth, indicated at 41, stretched over a triangular frame, the edges of the cloth being secured to the front and side bars of the triangular frame in any suitable manner.

Fuel tanks 44 are provided, preferably disposed in sets at each side of the axis of the 25 machine, each set comprising two tanks, supported on the cross bars of the upper aeroplane member and extending obliquely downward, being connected at their lower ends to the supply pipe 45 for the engine. 30 Each tank is triangular in horizontal cross section with the apex presented forwardly so as to minimize the air resistance, and each tank tapers downwardly to its outlet end, this construction eliminating the "wash" or 35 surging of the fuel in tipping of the machine and insuring maintenance of balance.

The operation is as follows: In starting 40 the machine, with the running wheels 24 and 26 on the ground and the machine thereby supported in slightly inclined position, as shown in Fig. 5, the motors are set in operation, and the forward propulsion of the machine by the operation of the fans 32 causes a reaction of the aeroplanes 1, 2 and 45 10, on the air by which the machine is lifted and sustained, the elevation of the machine being controlled by operation of the horizontal rudder 14 and the machine being steered by control of the vertical rudder 18. 50 The lower aeroplane members 2 being smaller than the upper aeroplane members 1, the air is given a fuller opportunity to act on the upper aeroplane members when the machine is tipped upwardly and is proceeding 55 forward and the predominant pressure thus exerted on the upper aeroplane members tends to hold the machine in stable condition, the center of gravity of the machine being considerably below the upper aeroplane members. This predominance of pressure 60 on the upper aeroplane members is also effective in holding the machine in stable position while gliding or while moving more or less directly downward, the resisting effect of the air in that case being mainly

presented on the upper aeroplanes and therefore considerably above the center of gravity of the machine, so that the machine will tend to set itself with the upper aeroplanes at right angles to the direction of gravity and will therefore present maximum resistance to the descent. The formation of the aeroplane members as triangles with their bases presented forwardly I have found to be especially adapted to flying or to gliding in a stable manner and with minimum resistance and deflection. This triangular shape of the aeroplane members is also of advantage in mechanical construction, as each side of the aeroplane acts as a brace to the other sides. 70 75 80

What I claim is:

1. In an aeroplane, the combination with a frame, of two triangular main aeroplane members connected at their forward ends to said frame and extending rearwardly therefrom, and a triangular rear aeroplane member connected at its forward end to the aforesaid aeroplane members intermediate their length and extending from such point of connection rearwardly beyond the rear ends 90 of said main aeroplane members.

2. In an aeroplane, the combination with a frame having upper and lower front bars, upper and lower rear bars, triangular upper and lower aeroplane members extending between said upper bars and between said lower bars provided with side bars extending obliquely rearward from the front bars and connected at their rear ends to the rear bar, said lower aeroplane members being smaller than the upper aeroplane members, and means extending from said lower bars to support the said lower aeroplane members. 95 100

3. In an aeroplane, the combination with a frame having upper and lower portions, two upper triangular aeroplane members supported on said upper frame portion, two triangular aeroplane members smaller than the upper aeroplane members and directly 110 beneath the respective upper aeroplane members and supported on said lower frame portion, a rear triangular aeroplane member connected to the upper frame portion and extending in the space between the rear portions of the main upper aeroplane members, and a horizontal rudder mounted below said rear aeroplane member to be angularly movable in a vertical plane, said aeroplane members and horizontal rudder being formed as 115 120 triangles with the base presented forwardly and with the apex at the rear.

4. In an aeroplane, the combination with a frame, of two triangular main aeroplane members connected at their forward ends to said frame and extending rearwardly therefrom, a triangular aeroplane member connected at its forward end to the aforesaid aeroplane members intermediate their length and extending from such point of connec- 125 130

- tion rearwardly beyond the rear ends of said main aeroplane members, motive devices and an aviator's seat on said frame below the level of the said aeroplane members.
- 5 5. In an aeroplane, the combination with a frame, of two triangular main aeroplane members connected at their forward ends to said frame and extending rearwardly therefrom, a triangular rear aeroplane member
- 10 connected at its forward end to the aforesaid aeroplane members intermediate their length and extending from such point of connection rearwardly beyond the rear ends of said main aeroplane members, lower aeroplane
- members below said main aeroplane members, said lower aeroplane members being triangular and being smaller than the said main aeroplane members, an aviator's seat and motive devices on said frame below the level of said main aeroplane members. 15
- 20 In testimony whereof, I have hereunto set my hand at Los Angeles, California, this 28th day of December, 1910.

DAVID LESLIE MOBLEY.
